UNITED STATES PATENT OFFICE.

ROBERT MCKENNA, OF WHITE, TENNESSEE.

BALL-GOVERNOR.

SPECIFICATION forming part of Letters Patent No. 310,838, dated January 13, 1885.

Application filed June 17, 1884. (No model.)

To all whom it may concern:

Be it known that I, ROBERT MCKENNA, a citizen of the United States, residing at White, in the county of Shelby and State of Tennessee, have invented a new and useful Improvement in Ball-Governors, of which the following is a specification.

My invention relates to an improvement in ball-governors, the object being to produce a governor which shall be simple and cheap of construction, efficient of service, and not liable to get out of order.

The invention consists in the construction and arrangement of parts, substantially as hereinafter set forth. I attain these objects by the mechanism illustrated in the accompanying drawing, in which the figure is a vertical sectional elevation of my improved ball-governor.

Similar letters refer to similar parts throughout the drawing.

A represents the stand, B the driving-shaft, b b the miter-gear, C the main shaft, D the arms pivot-block, E E the arms, F F the balls, and G the valve-stem, of my improved ball-governor, all of which are constructed, arranged, and, excepting valve-stem G, operated in a manner similar to that in which like parts are constructed, arranged, and operated in an ordinary ball-governor.

A novel and important principle of construction will now be explained in connection with the device as described. The upper part of main shaft C is a hollow square, W, in cross-section, the hollow being open throughout on the two sides. Valve-stem G is provided on a part of its length with a right-hand thread, h, and is also provided on another part of its length with a left-hand thread, g. These threads h and g are on the part of valve-stem G that is in hollow square W. A pair of jaws, o o, having a right-hand thread on their face, and a pair of jaws, p p, having a left-hand thread on their face, are pivoted in hollow square W. Two of these jaws—one of pair o o and one of pair p p—are joined together at their pivotal ends and pivoted midway of their united length vertically in line with valve-stem G. Their free ends flare backward, caus-

ing their backs to form an angle at their pivot N. The other two jaws—one of pair o o and one of pair p p—are pivoted and arranged in the same manner on the opposite side of valve-stem G. Two anti-friction-rollers, K K, adapted to the backs of jaws o o and p p, are journaled in and carried up and down by a roller-frame, M, which latter is made to fit and slide up and down on the square part of main shaft C. The upper ends of two connecting-rods, J J, are connected to the lower ends of roller-frame M by pins T T. The lower ends of said connecting-rods J J are connected to arms E E by pivots V V. A pin, S, secured on the lower part of valve-stem G and extending therefrom horizontally, prevents valve-stem G from turning by coming in contact with stand A. When the engine is in motion at the desired rate of speed, the balls F F will swing at an elevation that will bring anti-friction rollers K K into the angle formed by the backs of jaws o o and p p. A further out-throw of balls F F will, by raising arms E E, rods J J, and roller-frame M, roll anti-friction rollers K K upon the backs of jaws p p, closing jaws p p on valve-stem G, causing the left-hand thread on the face of jaws p p to mesh into the left-hand thread g on valve-stem G. While the threads are thus in mesh, jaws p p, by rotating round valve-stem G, which is prevented from turning by a pin, S, previously referred to, will press valve-stem G down, so as to adjust the governor-valve and regulate the speed of the engine. An infall of balls F F would roll anti-friction rollers K K down on the backs of jaws o o, closing them on valve-stem G, causing the right-hand thread on the face of jaws o o to mesh into the right-hand thread h on valve-stem G. While the threads are thus in mesh, jaws o o, by rotating round valve-stem G, will raise valve-stem G up, so as to adjust the governor-valve and regulate the speed of the engine. Arms pivot-block D is vertically adjustable on main shaft C, and can be retained after adjustment by a set-screw, R. Any desired rate of speed within the capacity of the steam and the engine can be attained by the adjustment of arms pivot-block D on main shaft C.

I claim as my invention, and desire to secure by Letters Patent—

In a ball-governor, the combination of jaws *o o* and *p p*, their pivots *N*, anti-friction rollers *K*, roller-frame *M*, connecting-rods *J*, and pins *T* and *V* with stand *A*, driving-shaft *B*, miter-gears *b*, main shaft *C*, arms pivot-block *D*, arms *E*, balls *F*, and valve-stem *G*, the lat-

ter having a right-hand thread, *h*, on a part of its length and a left-hand thread, *g*, on another part of its length.

ROBERT McKENNA.
